US00D619312S

(12) **United States Design Patent**
Rodenkirch et al.

(10) **Patent No.:** **US D619,312 S**
(45) **Date of Patent:** **** Jul. 6, 2010**

(54) **FLOOR FINISH APPLICATOR**

(75) Inventors: **Douglas S. Rodenkirch**, Sun Prairie, WI (US); **Scott I. Biba**, Highland, WI (US); **Craig P. Conner**, Madison, WI (US); **Daniel R. Nett**, Sun Prairie, WI (US); **Nicholas S. Reback**, Monona, WI (US)

(73) Assignee: **Diversey, Inc.**, Sturtevant, WI (US)

(**) Term: **14 Years**

(21) Appl. No.: **29/326,990**

(22) Filed: **Oct. 28, 2008**

Related U.S. Application Data

(63) Continuation of application No. 29/282,454, filed on Jul. 20, 2007, now Pat. No. Des. 580,605.

(51) **LOC (9) Cl.** **15-05**

(52) **U.S. Cl.** **D32/15**

(58) **Field of Classification Search** D32/15, D32/16, 20; D15/13; 401/48, 139, 146; 239/146, 148

See application file for complete search history.
